(57) **CLAIM**

The ornamental design for a mount for a charging station, as
shown and described.

DESCRIPTION

FIG. 1 is a first perspective view of a mount for a charging
station;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a perspective view of the mount of FIG. 1, shown
in an environment.

In the drawings, broken lines are for the purpose of illustrating
portions of the mount for a charging station that form
no part of the claimed design. In FIG. 7, the same type of
broken lines are used to show environment that forms no
part of the claimed design. Color is unclaimed and forms no
part of the claimed design.
